UNITED STATES PATENT OFFICE.

HARRY M. FRECK, OF COLUMBUS, OHIO.

PRINTING, DUPLICATING, AND ADDRESSING MACHINE.

1,228,425.

Specification of Letters Patent.

Patented June 5, 1917.

Application filed May 21, 1909. Serial No. 497,451.

To all whom it may concern:

Be it known that I, HARRY M. FRECK, a citizen of the United States, residing at Columbus, in the county of Franklin and State of Ohio, have invented certain new and useful Improvements in Printing, Duplicating, and Addressing Machines, of which the following is a specification.

This invention relates to the improvement of printing, duplicating and addressing machines, the object of the invention being to provide a device of this character adapted to print letterheads upon ordinary letter sheets and to simultaneously print the body 10 of an imitation typewritten letter through the medium of a ribbon and to also print the desired names and addresses upon said letter.

Further objects and advantages of the invention will be set forth in the detailed description which now follows.

In the accompanying drawings:

Figure 1 is a side elevation of a machine constructed in accordance with the invention,

Fig. 2 is a longitudinal vertical section upon line $x-x$ of Fig. 3, with certain of the parts in elevation.

Fig. 3 is a plan view thereof,

Fig. 4 is an end elevation looking from the left in Fig. 3 with the feed table removed,

Fig. 5 is a detail sectional view through the type bar delivering magazine,

Figs. 6, 7, 7^A and 8 are detail perspective views of yieldingly mounted type bar engaging members hereinafter described,

Fig. 9 is a horizontal section upon line $y-y$ of Fig. 5 with the type bars omitted,

Fig. 10 is a detail sectional view through the type bar receiving magazine,

Fig. 11 is a horizontal section upon line $a-a$ of Fig. 10,

Fig. 12 is a detail sectional view illustrating a pair of type bar supporting dogs hereinafter described,

Fig. 13 is a detail perspective view of one of the type bars,

Fig. 14 is an end elevation of cam members hereinafter described,

Fig. 15 is a section upon line $z-z$ of Fig. 1,

Fig. 16 is a detail perspective view of type bar releasing cams hereinafter described, and,

55

Fig. 17 is a detail view of bearing members hereinafter described.

Like numerals designate corresponding parts in all of the figures of the drawings.

The main frame of the machine, comprises side members 5 and end members 6, said end members lying below the side members and connecting said side members. The side members are channeled at 8 to form

ways for a sliding carriage 9. This carriage carries a chase 10 in which type 11 may be set to print the body portion of an imitation typewritten or circular letter through a ribbon 12, said ribbon extending between the ribbon rolls 13 and 14. Any desired means

60

may be provided for imparting an automatic feed to the ribbon rolls 13 and 14. I have shown mounted upon said rolls, ratchets 15 and 16 adapted to be engaged by pawls 17 and 18. These pawls are mounted

65

upon blocks 19 and 20 at opposite ends of the machine frame and may be adjusted toward or from the carriage by means of set screws 21. It is apparent that if the block 20 is set forward into position to en-

70

gage the ratchet of roll 14, the ribbon will be fed toward the right in Fig. 2, while if the block 19 is set forward for its pawl to engage the ratchet of roll 15, the ribbon will

75

be fed toward the left in Fig. 2.

80

A feed table 22 is mounted upon supports 23 and the sheets to be printed, may be fed from said table between the fixed gripper bar 24 and a movable gripper bar 25. The movable gripper bar 25 is carried by a

85

swinging arm 26 having its outer end beveled at 27 for engagement by the platen 28. The arm 26 is pivotally connected at 29 to the carriage 9 and has a tail 30 adapted to

90

contact with the stop 31 to limit the opening movement of the arm 26. This opening movement is accomplished by a spring 32. When at the limit of the movement of the carriage toward the left in Fig. 2, the beveled outer end 27 of the arm 26, passes from be-

95

neath the platen 28, the spring 32 acts to move the movable gripping bar 25 away from the fixed gripping bar 24. The sheets

100

to be printed may then be fed down the

table 22 between these gripper bars. As the carriage starts to move forward, the beveled end 27 of the arm 26 rides beneath the platen and presses the upper or movable 5 gripper bar down upon the fixed gripper bar. Of course, after the carriage moves a short distance toward the right in Fig. 2, the platen itself will engage the sheet and grip said sheet between itself and the type 10 11, thereby continuing the forward feeding of the sheet.

The carriage 9 has racks 33 upon its opposite edges, these racks being adapted to engage either the gear wheels 34 of the 15 platen or idler gears 35 that mesh with said platen, as will be hereinafter described. The platen and the gear wheels 35 are mounted respectively upon shafts 36 and 37. These shafts are journaled in swinging 20 brackets 38, said brackets in turn being journaled in bearings 39. By referring to Fig. 17, it will be seen that the swinging bracket 38 carries an eccentric 40, this eccentric forming the journal for said bracket in the 25 bearing 39. A stud 41 projects outwardly from the eccentric and has secured to its outer end an arm 42. The structure just described is duplicated on the opposite side of the machine and the same reference numerals have been applied to the parts upon the opposite side of the machine. A tie bar 43 connects the upper ends of the arms 42, so that they move in unison, as will be hereinafter set forth. A marker arm 44 loosely 30 encircles the eccentric and has pivoted thereon to a latch 45 adapted to engage a pin 46' of arm 42 (see Fig. 1). This marker arm is adapted to move over an arcuate rack 46 and carries a spring tongue 47 adapted to 35 engage said rack to hold the marker arm in any adjusted position. The lower ends of the swinging brackets 38 carry rollers 48 that travel upon ledges 49 of the reciprocating carriage 9. These ledges are cut out 40 at 50 and 51 to permit the rollers to drop when the platen gears are to be thrown into engagement with the racks, or when the idlers 35 are to be moved into mesh with the racks, as will be hereinafter set forth.

50 Hangers 52 are secured to the side members 5 of the main frame by screws 53, one of these hangers carrying the arcuate rack 46. These hangers have extended portions 54 and 55 that carry the side plates 56 and 57 of the type bar delivering and type bar receiving chambers hereinafter described. The type bar delivering chamber comprises the side walls 56 and the end walls 57'. The wall 56 is slotted at 58 to permit pins 59 carried by a plate 60 to project through said side wall and into the type bar delivering chamber. Located within the type bar delivering chamber and centrally riveted at 61 to the opposite sides thereof, are the spring 65 plates 62 (see Fig. 6). The upper ends of

these spring plates 62 are in turn riveted through openings 63 to U-shaped channels 64, the edges of the side walls of said channels being serrated as at 65. Centrally disposed within these channels and held in position by the slotted ends 66 of spring extensions 67 of plates 62, are the serrated bars 68. It will therefore be seen that the channels are yieldingly mounted from the side walls of the type delivering chamber and 70 that the serrated bars 68 are independently yieldingly mounted from said side walls in such manner that the serrated bars 68 which are engaged by the pins 59 at their lower ends (see Fig. 5), may be given an upward 80 movement to elevate the entire stack of address type bars 69. This entire stack of type bars is held in the position to which it is elevated by the serrations 65 engaging the extensions 70 of the individual type bars. 85

A bearing extension 71 has pivotally connected thereto a bell crank lever 72. A link 73 is pivotally connected at 74 to the carriage 9 and carries a roller 75 which when the carriage is moving toward the right in 90 Fig. 5, rides over the long arm of the bell crank lever and up into a recess 76 of the carriage, the pivotal mounting of the link 73 permitting the roller to do this, but when the carriage is moving toward the left in 95 Fig. 5, the roller engages the short arm of the bell crank lever and throws the longer arm of the bell crank lever upwardly to engage the underside of that type bar 78 that has been lifted to a sufficient height to be 100 engaged by the portion 79 of the carriage, this uppermost type bar being shoved along toward the left until it is partially free of the remaining type bars at which time the long arm of the bell crank lever engages its 105 underside and forces it up through a slot 80 in the carriage until the dogs 81 (see Figs. 5 and 12) engage beneath it and hold it in printing position beneath the ribbon 12, the type bar traveling with the carriage as will 110 be readily understood. A rod 82 extends from the bell crank lever to and through a lever 83 and has a spring 84 disposed between the outer end of said lever and its head 85 in such manner as to cushion the 115 movement of the lever 83. This lever 83 is pivotally connected at 86 with the plate 60 and is also pivotally connected at 87 with the side plate 56 of the type bar delivering chamber. A spring 88 is connected to said 120 lever 83 and to a portion 89 of the type bar delivering chamber. At its outer end the lever 83 carries a pawl 90, the nose of which is adapted to engage in notches 91 and 92 formed in the edge of the side plate 56. A 125 spring 93 normally tends to force said pawl into engagement with said notches, while a pin 94 mounted upon the lower end of a lever 95 is adapted to engage and release said pawl as will be hereinafter set forth. 130

The lever 95 is pivoted at 96 to the side wall 56 of the type bar delivering chamber and its upper end lies in the path of movement of a lug 97 that projects downwardly from the underside of the carriage 9. Mounted upon the shaft 37 (see Fig. 3) is a pulley 98 to which power may be applied by means of a belt, not shown. At its opposite end this shaft carries a pulley 99 that imparts movement to a larger pulley 100 by means of a belt 101. Mounted upon the shaft 102 of the pulley 100 is an inking roller 103, which together with a second inking roller 104 is mounted in a fountain or housing 105 adapted to receive ink. A swinging inking roller 106 is mounted upon a shaft 107 that is journaled in bearings 108 and 109. The bearing 109 is vertically channeled for the passage of a rack bar 110, said rack bar 20 meshing with a pinion 111 that is mounted upon the shaft 107. A spring 112^a encircles this shaft and normally tends to turn said shaft to throw the swinging ink roller over upon the ink rollers 103 and 104. This tendency of the ink roller 106 to swing over to the position just described, tends to turn the pinion 111 in such direction as to force the rack bar downwardly. Upon its lower end the rack bar carries a roller 113 (see Fig. 30 15). This roller is mounted upon a shaft 114 journaled in a lower end extension 115 of the rack bar and a spring 112 bears between a portion of this extension and a collar 117 of the shaft 114 and normally 35 tends to force said roller outwardly. This roller engages a cam member 118, said cam member being secured to and traveling with the carriage.

It is to be understood that the form from 40 which the letter head is to be printed in ordinary ink, is set in the portion 119^a of the chase or outside of the ribbon 12, consequently when the carriage and the chase are reciprocated, the cam member 118 acts to 45 move the rack bar upwardly and to thereby swing the inked roller 106 over into such position as to ink the form from which the letter head is to be printed.

This is accomplished in the following 50 manner: As the cam 118 moves toward the left in Fig. 1, the roller rides up the face 119 thereof and along the surface 120 thereof. The movement of the roller up the face 119 moves the rack bar and the pinion in such 55 manner as to throw the roller 106 inwardly and downwardly into position to ink the type comprising the letter head, as the carriage moves toward the left in Fig. 1. When the roller reaches the surface 121, 60 which it will be noted by referring to Fig. 14, is beveled, the spring 112^a causes the roller 113 and rack bar to move bodily down said inclined surface until the roller rests upon the surface 122. Then the direction 65 of movement of the carriage changes as will

be hereinafter set forth and the cam 118 moves toward the right in Fig. 1 and the roller moves along the surface 122, it being understood that at this time the roller 106 rests upon the inking rollers 103 and 104. 70 The lugs 126 projecting from the outer faces of the swinging brackets 38 move in cut-out portions of the bearings 39. Springs 123, 124, are disposed between these lugs and the walls of the cut-out portions of the bearings 75 39 and serve a purpose hereinafter described.

The operation of the machine as so far described, is as follows:

With the parts in the position shown in Figs. 1 and 2, the platen gears are in 80 mesh with the teeth of the racks. Power being applied to the pulley 98, said pulley rotates the shaft 37 and the gears 35 and through said gears, rotates the platen gears in the direction of the arrow in Fig. 2. This 85 causes the carriage to move toward the right in Fig. 1. During this movement of the carriage toward the right, the rollers 48 ride upon the surfaces 49 of the carriage and hold the swinging brackets 38 in such position as to maintain the gears 34 in mesh with the racks. When the carriage reaches its limit of movement toward the right, however, and the cut-out portions 51 come beneath the roller 48, the spring 123 which 90 has been under slight tension, acts to move the swinging brackets to thereby swing the gears 35 into mesh with the racks and to swing the gears 34 out of mesh with said racks. This will reverse the direction of 95 movement of the carriage, as will be readily understood and drive it in the opposite direction. As soon as the rollers 48 ride out of the depressions 51, the springs 124 are placed under slight tension and the meshing of the gear wheels 35 with the racks, is rendered secure and firm. It is to be understood that the lug 126 (see Fig. 17) is carried by the swinging bracket and that the springs 123 and 124 bear between this 100 110 lug and the fixed bearing member 39. The pressure with which the platen bears upon the ribbon and consequently the pressure with which the sheet to be printed is forced against the ribbon and the type, is controlled and may be varied by the lever 42, it being apparent that swinging said lever, results in rotating the eccentric in its bearing and since said eccentric carries the bearing for the swinging brackets, said swinging 115 120 brackets may be moved bodily toward or from the carriage. Of course this movement need be but a very slight one.

The purpose of the marking lever 44 is to 125 indicate the point at which the platen pressure has been set, so that if it becomes necessary to entirely relieve the platen pressure for the purpose of removing a torn sheet, the same pressure may be again had without experiment. If, for instance, the marking 130

lever 44 has been set in any given position and the lever 42 is swung to entirely release the platen pressure, by again returning said lever to such position that the latch of the 5 lever 44 engages the pin 46' of lever 42, the same pressure may be secured. It is apparent that when the sheets are fed down the table 22 until they are engaged by the gripper bars and are drawn beneath the platen, 10 the body portion of an imitation typewritten letter will be imprinted upon the underside of said sheet by the ribbon being forced against the underside of said sheet which is backed by the platen, by the type 11. At 15 the same time that the previously inked form, set up in the space 119^a of the chase, prints the letter head that portion of the ribbon that overlies the addressing type bar, which is forced upwardly through the opening 127 of the bottom of the chase (see Fig. 3), serves when pressed against the underside of the sheet by said addressing type bar, to fill in the address on the letter. As the carriage moves toward the rear of the 20 machine in Fig. 3, the edge of the printed sheet, rides up over the fingers 128 of a fly 129, this fly being journaled in bearings 130 of the main frame of the machine and being provided with a pinion 131 which meshes 25 with a short rack 132 carried by a longitudinally extending bar 133. This bar is cut out upon its underside as at 134 to permit the lug 135 of the carriage to travel between downward extensions 136 thereof. It 30 will therefore be seen that the carriage at its rearmost limit of movement, will engage the downward extension 136 to shift the longitudinally extending bar and its rack and thereby rotate the pinion in such manner as to swing the fly over and deposit the 35 printed sheet right side up upon a table or other support, not shown. It will be understood that the fly lies in a horizontal position and in a position to have the downwardly curved ends of its fingers slide beneath the front end of the sheet as the carriage moves toward said fly.

The means for releasing the addressing type bar from the carriage and for depositing it in the type bar receiving chamber, 50 will now be described: Pivoted at 137 upon the underside of the carriage, are levers 138, the tails 139 of which are adapted to be engaged by an upstanding lug 140 of 55 the rear cross bar of the machine frame, to thereby force the ends 141 of said levers together. As these ends move together, they engage the tails of the dogs 81 to rock said dogs upon their pivots 142 to 60 thereby release the addressing type bar and permit said type bar to fall out of the opening 127 and upon a table 143, this table being located within the type bar receiving chamber. This table is supported 65 by cables 144 that pass over pulleys 145,

said cables having weights 146 attached to their lower ends. Latches 147 are adapted to engage the outstanding portion 70 of the addressing type bars to hold the table down against the action of the 70 weights 146 as said type bars are pressed downwardly by means which will now be described.

Secured to plate 57 of the type bar receiving chamber, is a keeper 148 in which slide 75 the ends 149 of wires 150. These wires are coiled at 151 and their lower ends outturned at 152 and have a spring 153 secured thereto, the opposite end of said spring being secured to a pin 154 carried by the keeper 80 148. The upper ends of the wires 150 are connected by a cross bar 155 (see Fig. 16) and this cross bar carries a knob 156. The carriage 9 carries a fixed cam 157 and a pivoted cam 158 and as this carriage reciprocates, the pivoted cam engages the knob 156 and forces the inturned ends 157' of the wires inwardly until they overlie the uppermost type bar that has been dropped from the opening 127. Immediately thereafter 90 the fixed cam 157 acting upon the knob 156 by means of the undercut portion 156^a (shown dotted in Fig. 16) forces said knob and the wires 150 downwardly against the tension of the spring 153 and since these 95 wires rest upon the uppermost type bar, all of the type bars and the table 143 are forced downwardly against the action of the weights 146 until the latches 147 engage over the extensions 70 of the next higher 100 type bars preparatory to the operation being again repeated. When the lug 97 of the carriage contacts with the upper end of the lever 95, the pin 94 releases the pawl from its engagement with the notch 92 and permits the spring 88 to throw said pawl up into engagement with the notch 91. This of course imparts an upward movement to the plate 60, through the medium of the pin 86 and elevates the next succeeding type 110 bar into position to be carried by the portion 79 of the carriage, to such position that it may be engaged by the upper end of the longer arm of the bell crank lever 72 as has been hereinbefore described, it being apparent that this operation may be repeated 115 as long as there are any of the addressing type bars left in the type bar delivering chamber.

By referring to Fig. 13, it will be seen 120 that the type 70', comprising the addressing type bar, are L-shaped and that the printing surfaces are formed upon the outer face of one of the longer arms of said type. These type engage recesses 70" of the type 125 bar 70"". A plate 70"" holds these type in position, but it is to be understood that the invention is not limited with relation to the kind of type employed, for any method of supporting the type in the type bars may 130

be employed or the bars may have the printing faces formed integral thereupon.

In Fig. 2 of the drawing, I have shown a form-kerf such as has been illustrated in 5 my co-pending application, Serial Number 485,706, filed March 25, 1909, though it is to be understood that I do not desire to limit myself to the use of this particular form of printing element in the chase or carriage. 10 In this specification and in the accompanying claims, the term "chase" is to be construed to mean any recessed member whether integral with the carriage or separate therefrom and carried thereby adapted to receive 15 a printing element.

From the mechanism described, it is possible to reproduce in large quantities and very rapidly, the body of a circular letter, insert the individual names and addresses 20 at the top of each letter by means of the addressing plate having similar type characters, print the letter-head, and reproduce a fac-simile of a written signature at the bottom of the letter. In this manner a letter 25 may be reproduced which has every appearance of original typewriting, type-characters and an inking ribbon similar to those used by an ordinary typewriter, being used.

30 This resemblance is attained by the contact of the rolling platen this machine gives, and the same shade of color on the body of the letter as on the address at the top, this being very essential.

35 It will also be seen that by having the inking-ribbon made in colors, and the manner in which it travels across the type form, two or more colors may be reproduced simultaneously. A different color may also 40 be used for the inking roll.

From the foregoing description, it will be seen that simple and efficient means are herein provided for accomplishing the objects of the invention, but while the elements shown and described are well adapted 45 to serve the purposes for which they are intended, it is to be understood that the invention is not limited to the precise construction set forth, but includes within its 50 purview such changes as may be made within the scope of the appended claims.

What I claim, is:

1. A printing machine comprising a frame, a reciprocable carriage, forward and reverse 55 gears, separate shafts for supporting said gears, means coöperating with either of said gears for driving said carriage, an element carrying said shafts and adjustable to render either the forward or reverse gear operable 60 by disengaging one and engaging the other with said means, said carriage and element being complementally formed to automatically effect such adjustment at the end of movement of said carriage in either direction. 65

2. A printing machine comprising a frame, a reciprocable carriage, forward and reverse gears, separate shafts upon which said gears are mounted, means coöperating with either of said gears for driving said carriage, an element carrying said shafts and adjustable to render either the forward or reverse gear operable by disengaging one and engaging the other with said means, irregularities on said carriage operative on said element at 70 the end of movement of said carriage in either direction to effect such adjustment. 75

3. A printing machine comprising a frame, a reciprocable carriage, forward and reverse gears, separate shafts upon which said gears are mounted, means coöperating with either of said gears for driving said carriage, an element carrying said shafts and adjustable to render either the forward or reverse gear operable by disengaging one and engaging the other with said means, a trip element on 80 said first named element, and an irregularity at each end of said carriage coöperative with said trip element to effect adjustment of said first named element automatically. 85

4. A printing machine comprising a frame, a reciprocable carriage, forward and reverse gears, a flat faced rack section carried by said carriage for coöperation with said gears, and a tilttable supporting element for 90 said gears movable to engage either gear with said rack, said carriage being structurally formed to adjust said element at the end of its movement in either direction. 95

5. A printing machine comprising a frame, 100 a reciprocable carriage, forward and reverse gears, a flat faced rack section carried by said carriage for coöperation with said gears, a tilttable supporting element for said gears movable to engage either gear with 105 said rack, and a trip arm on said element, said carriage being complementally formed to automatically move said arm and tilt said frame to its position of adjustment at the end of movement of the carriage in either 110 direction.

6. A printing machine comprising a frame, a reciprocable carriage, forward and reverse gears, a flat faced rack section carried by said carriage for coöperation with said gears, a tilttable supporting element for said gears movable to engage either gear with 115 said rack, and a trip arm on said element, said carriage being formed with a depression at either end to trip said arm and element. 120

7. A printing machine comprising a frame, a reciprocable carriage, forward and reverse gears, a flat faced rack section carried by said carriage for coöperation with said gears, a tilttable supporting element for said gears movable to engage either gear with 125 said rack, and means for yieldably maintaining said element against tilting, said carriage normally maintaining said element 130

tilted but being constructed to automatically release said element and shift the direction of tilting pressure.

8. A printing machine comprising a frame, a reciprocable carriage, forward and reverse gears, a flat faced rack section carried by said carriage for coöperation with said gears, a tiltable supporting element for said gears movable to engage either gear with said rack, means resiliently centering said element, and a trip arm, said carriage being constructed to strike said trip arm and tilt said element in opposite directions at opposite ends of the travel of the carriage.

15 9. A printing machine comprising a frame, a reciprocable carriage, a roller platen having a gear for driving said carriage in one direction, a second gear for driving the carriage in a reverse direction, a tiltable frame 20 for supporting said platen and gears, and means for tilting said frame at one end of the movement of said carriage to render said platen gear operative and drive said carriage forward and at the other end of 25 movement of the carriage to reversely drive said carriage by the other gear and render said platen inoperative.

10. A printing machine comprising a base, a reciprocable carriage, a driving member 30 for said carriage comprising a roller platen carrying a gear and a supplemental gear in mesh therewith, and means operative upon the approach of the carriage to either end of its reciprocation to move one of said gears 35 into operative relation to said carriage.

11. A printing machine comprising a base, a reciprocatory carriage having a rack thereon, a gear frame pivotally supported on said base, intermeshing driving gears on said 40 frame, means operative by said carriage in its reciprocation to throw one of said gears into operative relation to said rack at either end of such reciprocation.

12. A printing machine comprising a base, 45 a reciprocating carriage having a rack thereon, a gear frame pivotally mounted on said base, intermeshing driving gears on said frame, resilient centering means for said frame, a depending element on said frame 50 normally bearing against said carriage to maintain said frame off of its center and maintain one of said gears in operative relation to said rack, said carriage having cut-away portions at either end to permit pivotal swinging of said frame under force of said compressed centering means to carry the opposite gear into coactive relation with said rack.

13. A printing machine comprising a base, 60 a reciprocatory carriage having a rack thereon, a gear frame pivotally mounted on said base, intermeshing driving gears on said frame, a depending element on said frame normally bearing against said carriage to 65 maintain said frame off center and thereby

maintain one of said gears in operative relation to said rack, said carriage having cut away portions therein at either end to permit pivotal swinging of said frame into position to carry the opposite gear into coactive relation with said rack. 70

14. A printing machine comprising a base, a reciprocatory carriage having a rack thereon, a gear frame pivotally mounted on said base, intermeshing driving gears on said 75 frame, a depending roller element on said frame normally bearing against said carriage to maintain said frame off center and thereby maintain one of said gears in operative relation to said rack, said carriage 80 having cut-away portions therein at either end to permit pivotal swinging of said frame into position to carry the opposite gear into coactive relation with said rack.

15. A printing machine comprising a base, 85 a reciprocable carriage, a gear frame, intermeshing gears in said frame, a rack on said carriage adapted to be driven by said gears, eccentric bearings for said frame, and a lever for controlling the location of said bearings 90 to elevate or lower said frame.

16. A printing machine comprising a base, a reciprocatory form carriage, a roller platen, adjustable eccentric mountings for said roller platen to adjust said platen vertically with respect to said carriage, a lever for controlling the position of said 95 mountings, and a marking bar coacting with said lever to indicate any selected position of adjustment of a comparatively permanent 100 nature.

17. A printing machine comprising a base, a reciprocatory form carriage, a roller platen element, adjustable eccentric mountings for said roller platen element to control its 105 adjustment vertically with respect to said carriage, a rack segment, a marking bar for adjustment to any point on said segment, a lever for controlling the position of said mountings, and a means for coupling said 110 lever to said marking bar.

18. A printing machine comprising a base, a reciprocatory form carriage, a roller platen element, adjustable eccentric mountings for said roller platen element to control its 115 adjustment vertically with respect to said carriage, a rack segment, a marking bar for adjustment to any point on said segment, a lever for controlling the position of said mountings, and a latching device for latch- 120 ing said lever to said marking bar.

19. In a printing machine, the combination of a base, a roller platen, a printing form element having a reciprocatory movement, spools on the ends of said element, a 125 ribbon carried by said spools and extending across the face of the type, and a means for inserting a section of printing surface in the form of said element from the under side thereof. 130

20. A printing machine comprising a frame, a traveling bed, a platen, and a shiftable multi-color ribbon, said bed being constructed to receive the type in lines disposed parallel to the direction of shifting of said ribbon whereby one or more lines may be printed of a different color from the body of the form.
21. A printing machine comprising a frame, a traveling bed, a platen, and an automatically shiftable multi-colored ribbon, said bed being constructed to receive the type in lines disposed parallel to the direction of shifting of said ribbon, said bed also traveling in a direction parallel with the direction of shifting of said ribbon.
22. A printing machine comprising a reciprocating form having an opening therein, an inking ribbon mounted on the upper
- side of said form, a plurality of type elements, and means for inserting said type elements into the opening in said form to a printing level from the underside thereof.
23. A printing machine comprising a reciprocating form having an opening therein, an inking ribbon mounted on the upper side of said form, a plurality of type elements, and means for automatically and successively inserting said type elements into the opening in said form to a printing level from the underside thereof.

In testimony whereof I affix my signature in presence of two witnesses.

HARRY M. FRECK.

Witnesses:

L. CARL STOUGHTON,
A. L. PHELPS.
